UNITED STATES PATENT OFFICE

FRED I. RAYMOND, OF RIVER FOREST, ILLINOIS

SODA FOUNTAIN

Application filed March 18, 1929. Serial No. 347,947.

This invention relates to soda fountains, or similar refrigerating apparatus, and more particularly to new and improved mechanism for automatically and simultaneously maintaining different selected temperatures in different compartments or portions of the apparatus.

In the modern soda fountain, it is often desirable that several different temperatures, all below the prevailing atmospheric temperature, be maintained in different portions of the fountain, for example in the compartment for storing brick ice cream, the compartment for storing bulk ice cream, the compartment or tank for cooling the soda and the drinking water, the compartment where the syrups are stored, and the general storage compartment for bottled goods and similar articles. It is especially difficult to maintain the soda and drinking water at the substantially constant and proper temperature, due to the fact that the cooled supply of these liquids is being intermittently drawn upon in varying amounts.

According to the present invention, the coolers or coils through which the soda or drinking water pass, are positioned in a tank containing refrigerating brine. The temperature of this brine is maintained either by controlling the flow of the brine itself into and out of the tank, or by placing the controlled refrigerating element within the brine in the tank. Thermostatic means is provided for controlling the flow of either the brine or the refrigerating fluid which cools the brine, and this thermostatic means is responsive simultaneously to both the temperature of the water or soda in the coolers, and also the temperature of the brine in the tank.

The invention also contemplates a refrigerating apparatus provided with a boiler or other refrigerating element or group of such elements in only that compartment wherein the lowest temperature, is to be maintained, the desired temperatures in the other compartments being maintained by controlling the flow of brine or similar cooling fluid from this main compartment to and back from the other compartments of the soda fountain.

The general object of this invention is to

provide a new and improved refrigerating system for soda fountains or similar apparatus, substantially as referred to hereinabove and as described more in detail in the specifications which follow.

55

Another object is to provide a system embodying automatic means for controlling the temperature of a cooling medium in response to the simultaneous and cumulative temperature changes in the medium itself and also in the liquid that is being cooled by this medium.

60

Another object is to provide an improved soda fountain that will automatically and simultaneously maintain a plurality of different temperatures in the several different compartments thereof.

65

Another object is to provide improved means for positively maintaining a circulation of brine in the several cooling tanks.

70

Another object is to provide improved means for maintaining a circulation of brine through a thermo-siphon coil used for cooling one of the compartments of the fountain.

75

Other objects and advantages of this invention will be more apparent from the following detailed description of certain approved forms of apparatus operating according to the principles of this invention.

80

In the accompanying drawings:

Fig. 1 is a view, partially in elevation, and partially in vertical section, of a soda fountain, showing diagrammatically the cooling system therefor.

85

Fig. 2 is an enlarged vertical section showing one form of thermostatically controlled valve-operating mechanism.

90

Fig. 3 is a similar view showing a different form of thermostatic mechanism.

Fig. 4 is a plan view of one of the coolers.

Fig. 5 is a section through one of the coolers showing a different form of bulb mechanism.

95

Fig. 6 is a similar view through a pair of coolers, showing thermostatic bulbs connected in multiple.

Figs. 7, 8, 9 and 10 are partial vertical sections showing modified forms of the refrigerating apparatus.

100

Referring first to Fig. 1, which shows a preferred form of apparatus, the soda fountain comprises a larger lower portion 1, housing a plurality of separate compartments for storing and cooling different materials, this portion having a top 2 in the form of a horizontal shelf provided with openings for gaining access to certain of the compartments, and a front upwardly projecting portion 3 providing a compartment for the syrup dispensers 4 and from which project the draft arms 5 and 6 for dispensing soda and ice water respectively. Certain of the walls of the soda fountain may be made double as indicated at 7 and 8, the space between being filled with insulating material 9. It is to be understood that the refrigerating apparatus and the fluid and electric circuits are illustrated diagrammatically, and not in the size, relative proportions and exact locations, that would be found in an actual construction.

A main compartment or tank 10 is adapted to be filled with brine in which is positioned a receptacle or freezer 11 for holding brick ice cream. Access to this receptacle is through an opening in the top 2 of the fountain. It is desirable that the temperature in this tank or compartment 10 be kept quite low, for example from 0° to 5° Fahrenheit. Within the brine in this compartment 10 is positioned some suitable form of refrigerating element, such as the "boiler" shown at 12. This boiler is in the form of a coil or assemblage of grouped tubular members in which a compressed and liquefied material admitted through the inlet supply pipe 13 expands and vaporizes, the gas passing out through pipe 14. The process of expansion of this refrigerating medium serves to absorb heat from the brine in tank 10, in a well known manner. A temperature regulating control valve 15 in supply pipe 13 serves to limit the flow of the refrigerating medium to the boiler and thus regulates the temperature that is maintained in the brine tank 10. It is to be understood that the refrigerating element just described is shown by way of example, and that any other form of refrigerating means might be used for maintaining the brine in tank 10 at the proper temperature. It is to be understood that the term "boiler" as used in the following description and in the claims is intended to designate any equivalent form of refrigerating element for keeping the brine or other fluid in the tank at the proper low temperature.

A second compartment or brine tank 16 positioned adjacent the main tank 10 is adapted to house one or more freezers 17 for holding bulk ice cream. The temperature in this compartment should be somewhat higher than in compartment 10, for example from 10° to 12° Fahrenheit. A return port or passage 18 is formed in the wall 19 separating

the tanks 10 and 16, and the brine that flows back into tank 10 from tank 16 through the passage 18 is deflected upwardly by the baffle plate 20.

An auxiliary brine tank 21 for cooling the soda and drinking water is positioned at one side of or in one corner of the large compartment 22 which is used for general storage purposes. The soda and plain water that are refrigerated by the brine tank 21 should be kept at a temperature of from 33° to 40° Fahrenheit, whereas a temperature of from 40° to 45° Fahrenheit is proper in the refrigerating compartment 22. This compartment 22 is cooled by conduction from the brine tank 21 positioned therein. Positioned within the brine tank 21 are two similar but separate coolers 23 and 24 through which the soda and plain water respectively are circulated. The soda flows in through pipe 25 from the source of supply so as to replenish the soda drawn off from the cooler 23 through pipe 26 leading to the draft arm 5. Similarly, the plain water flows in through pipe 27 to cooler 24, and is drawn off from the cooler through pipe 28 leading to the faucet or draft arm 6. The coolers 23 and 24 may be of the general construction illustrated in Fig. 4, consisting of a plurality of tubes or cylinders 29 connected by end heads 30.

The upper compartment 31 in which the syrup dispensers 4 are positioned, need not be kept at as low a temperature but will be from 20° to 30° under the room temperature.

The mechanism for maintaining these different temperatures in the different compartments of the fountain will now be described.

A pipe or conduit 32 leads from the lower portion of brine tank 10 to a pump 33 constantly driven by a small electric motor 34.

The brine drawn from tank 10 through conduit 32 is forced by pump 33 through a conduit 35 having branches 36 and 37 leading respectively to the two similar two-way valves 38 and 39. One of these valves is indicated in vertical section in Figs. 2 and 3, and comprises an inlet passage 40 leading to a central chamber 41 from which lead an upper outlet passage 42 and a lower outlet passage 43. A ball valve 44 is adapted to alternatively close one or the other of the passages 42 and 43, the movable valve member having a stem 45 leading to the core 46 of a solenoid 47. When the solenoid 47 is deenergized, the valve 44 will be lowered so as to close the lower outlet passage 43 and open the upper outlet passage 42. When the solenoid 47 is energized, the valve 44 will be raised to close the upper passage 42 and open the lower passage 43. The other valve 39 is of exactly similar construction and is similarly controlled by a solenoid 48. The upper outlet passages 42 of each valve connect with a return conduit 49 which leads back to the upper portion of brine tank 10. Therefore, when both

valves are in their lowered positions, all of the brine withdrawn from tank 10 through conduit 32 will be forced back into the upper portion of tank 10 through the return conduit 49. Although no brine is being supplied at this time to either of the tanks 16 or 21, the forced circulation of brine to and from tank 10 through the conduits 32 and 49 will serve a useful purpose by keeping the brine solution in motion so as to prevent the salts from settling out to the bottom of tank 10.

A brine conduit 50 leads from the lower outlet 43 of valve 39 into the upper end of the secondary brine tank 16. A thermostatic mechanism comprises a bulb 51 positioned within the brine in tank 16 and connected by tube 52 with an expandible and contractible element 53, here shown in the form of a Bourdon tube having one end anchored and the other end adapted to open and close a switch 54 positioned in the operating circuit of the solenoid 48. Switch 54 will normally be open and the solenoid 48 deenergized. Since no refrigerating element such as 12 is placed directly within the brine in tank 16, this brine will assume a somewhat higher temperature than the brine in tank 10. When a certain temperature has been reached, the expandible or vaporized thermostatic fluid in the bulb 51 and tube 53 will expand so that the tube 53 will tend to uncoil and thus close the switch 54 and complete the circuit energizing the solenoid 48. Brine will now be forced by pump 33 through conduit 37, valve 39 and conduit 50 into the tank 16, to replace brine that flows from tank 16 through passage 18 back into the main brine tank 10. The brine in tank 16 will thus be replaced by brine at a lower temperature drawn from the main tank 10, and when the desired low temperature has been reestablished in secondary tank 16, the thermostatic elements will open the switch 54 thus deenergizing the solenoid 48 and lowering the valve 44 so as to cut off the flow of brine to tank 16.

In a similar manner, a conduit 55 leads from lower outlet 43 of valve 38 into the auxiliary tank 21, and a return conduit 56 leads from the lower portion of this auxiliary tank into the main return conduit 49 and thence back into tank 10. When solenoid 47 is energized and the ball valve 44 raised, there will be a circulation of brine from tank 10 into and through the auxiliary tank 21 and thence back through return conduits 56 and 49 to tank 10. When sufficient of the brine in tank 21 has been replaced by colder brine from tank 10, the solenoid 47 will be deenergized and the flow of brine into tank 21 through conduit 55 will be cut off. Due to the variable rate at which soda or plain water is withdrawn from the coolers 23 and 24, the proper temperature of these liquids cannot be accurately maintained by merely keeping the brine within tank 21 at a sub-

stantially constant temperature, as is sufficient in the secondary tank 16. If the liquid in the coolers is rapidly withdrawn and hence replaced by warmer liquids from the source of supply, it is desirable that the temperature of the brine in tank 21 be rapidly lowered so as to hasten the cooling of the liquids in the coolers. On the other hand, if there is a small drain on the liquids in the coolers, that is if only a small amount of soda and water is being used, the brine in tank 21 may be permitted to rise to a somewhat higher temperature. To accomplish this result, the tank 21 is made of relatively small volume so that the brine therein may be rapidly replaced by a colder brine, and a dual thermostatic control is utilized that is responsive to the temperature condition of both the liquid in the coolers and also the temperature of the brine in tank 21. For this purpose an instrument is utilized of the type disclosed and claimed in my copending applications Serial No. 244,225, filed January 3, 1928, and Serial No. 313,493, filed October 19, 1928. Two different types of apparatus suitable for this purpose are disclosed in Figs. 2 and 3 of the drawings. Referring first to Fig. 2, a Bourdon tube 57 has its open end 58 anchored within the casing 59, this open end 58 being connected through tube 60 with the bulb 61. The bulb and Bourdon tube contain a thermostatic fluid which expands when heated. The closed inner end of tube 57 is connected with crank arm 62 which will be oscillated as tube 57 tends to coil or uncoil in accordance with temperature changes. A similar thermostatic unit comprises Bourdon tube 63, bulb 64, and crank arm 65, which is oscillated in accordance with changes in temperature of the medium in which bulb 64 is placed. The crank arms 62 and 65 are connected through links 66 and 67 respectively with the ends of a floating link 68, which in turn is connected through link 69 with a lever 70 which carries through clip 71 the tube 72 of a mercury switch. A mercury globule 73 in tube 72 is adapted to bridge two spaced contacts 74 and 75 in one end of tube 72, when the tube is tilted in the proper direction. When the tube is tilted in the other direction the mercury globule will run to the other end of the tube and break the circuit. The fulcrum 76 of lever 70 may be adjustably positioned in any one of a plurality of openings 77 in a bracket 78, and in a similar manner the upper end 79 of link 69 may be connected in any one of a plurality of openings 80 in the floating link 68. It will be apparent that the cumulative effect of the oscillations of the two crank arms 62 and 65 due to the movements of the two thermostatic units, will be imparted to the floating link 68 and thence through link 69 to the lever operated switch. If link 69 were connected to the exact center

of floating link 68, a certain temperature increase imparted to one thermostatic unit would be exactly balanced by a similar temperature decrease imparted to the other 5 thermostatic unit and no bodily movement of link 68 except a turning movement about its center would result, so that no movement would be imparted to the switch. The movement that is given to the switch will always be the net or algebraic sum of the movements imparted by the two thermostatic units. By suitably adjusting the connections 76 and 79, the relative effects of the 10 two thermostatic units, as applied to the switch operating mechanism, can be varied. The contacts 74 and 75 of the mercury switch are connected by flexible wires 81 and 82 to the binding posts 83 and 84 which are connected in the operating circuit for solenoid 47.

In the alternative form of mechanism shown in Fig. 3, the bulbs 61 and 64 are connected through tubes 85 and 86 with a single thermostatic coil or Bourdon tube 87, the 25 free end of which is adapted to actuate the arm or pointer 88 which carries one switch contact 89. An adjustable arm or pointer 90, movable over an index scale 91 carries the other switch contact 92. The bulbs 61 30 and 64 and the thermostatic coil 87 are all in open communication with one another through connecting tubing so that an expansion of the thermostatic fluid in one bulb 61 might be just counteracted by a contraction 35 of the fluid in bulb 64 and no movement would be imparted to coil 87. The expansion or contraction of coil 87 will always represent the net or algebraic sum of the temperature responsive movements of the fluids 40 in the two bulbs 61 and 64. The temperature at which the switch will be closed may be adjusted by moving arm 90 along the index scale 91. As a result of a sufficient rise in 45 temperature, the contacts 89 and 92 will be brought together so as to close the operating circuit of solenoid 47 and lift the valve member 44, as illustrated in Fig. 3.

The thermostatic bulb 61 is placed in the 50 brine in auxiliary tank 21, and the other bulb 64 is placed within one of the coolers 23 or 24. As shown in Fig. 1, it is placed within the clear water cooler. It could alternatively be placed within the soda cooler, or separate bulbs such as 64a and 64b (Fig. 6) could be 55 placed in each of the coolers 23 and 24, the tubes leading from these bulbs being connected, as at 93, 94 and 95 to a single tube leading to the thermostat coil. This is the same as 60 dividing the bulb 64 into two parts, one in each of the coolers, so that the responsive temperature will be that of the average of the liquid in the coolers. The bulb 64 might 65 be placed in one of the intermediate tubes of the cooler, as in Figs. 1 and 6, or may be elongated as indicated at 64c in Fig. 5 to

extend through one of the connecting heads, or through a plurality of the tubes.

It will now be apparent that the control of valve 38 for admitting new refrigerated brine to tank 21 is dependent not only on the temperature of the brine in the tank but also on the temperature of the liquid in the coolers. The brine in tank 21 may be sufficiently cold to maintain the desired temperature in the coolers when no liquid is being withdrawn therefrom, but assuming that there has been a steady withdrawal of soda or water from the coolers so that warmer liquid has flowed in from the source of supply, it is desirable that the temperature of the 70 brine in tank 21 be lowered considerably to quickly cool this new supply of liquid in the coolers. Under such circumstances, the bulb 64 in the cooler will react, through the thermostatic fluid therein, to cause the valve member 44 in valve 38 to be elevated, so that brine from tank 10 will be pumped through conduit 55 into auxiliary tank 21, the warmer brine being forced out through conduit 56 and return conduit 49 back into the upper 75 portion of tank 10. Since tank 21 is of relatively small volume, preferably holding about the same volume of brine as the volume of liquid in the coolers, the brine therein will be quickly replaced by much colder brine so that the new supply of liquid in the coolers will have its temperature quickly lowered to the desired point. The valve 38 will be operated to cut off the flow of new brine into 80 tank 21, and the temperature of the brine in tank 21 may be permitted to raise considerably before new brine is admitted, so long as its temperature is adequate to maintain the liquid in the coolers at the desired low temperature. In other words, when the liquid in 85 the coolers is at the proper temperature, the brine in tank 21 may be permitted to rise in temperature to approximately the same temperature as that in the coolers, but when considerable liquid is being withdrawn from the coolers, the temperature of the brine in tank 21 must be lowered so as to provide a 90 medium for cooling the new liquid admitted to the coolers. The simultaneous and dual control of the two thermostatic elements 61 and 64 operate to maintain a practically continuous supply of soda and water at the desired temperature. Another reason for having tank 21 of relatively small volume is to 95 avoid the possibility of freezing the water in the coolers. If the flow of water through the coolers is abruptly stopped, the brine temperature will rise at approximately the same rate as the water temperature falls.

In order to partly refrigerate the compartment 31 in which the syrup dispensers are located, a thermo-siphon loop consisting of pipes 96, 97, 98 and 99 extends from the upper portion of auxiliary pipe 21 and leads back thereinto. The return pipe 99 of this 100

thermo-siphon loop is positioned closely adjacent to the return conduit 49 leading from the pump back to tank 10. In the example here shown, these two pipes 99 and 49 are bound together by a wire or other connection indicated at 99^a. Under normal conditions, when brine is not being supplied to the auxiliary tank 21, the brine flowing through return pipe 49 will be at substantially the low temperature of the brine in tank 10, and will thus serve to chill or lower the temperature of the brine in leg 99 of the thermo-siphon loop so as to insure a flow of brine through this loop in the direction of the arrows.

In the general operation of the soda fountain disclosed in Fig. 1, the control valve 15 will be adjusted so as to cause the boiler 12 to maintain the brine in the main tank 10 at the desired low temperature. The pump 33 will cause a practically continuous flow of liquid from tank 10 and through the return conduit 49 to the upper portion of tank 10. This serves to keep the brine in circulation and prevent settling out of the salts, and also serves to chill the return leg of the thermo-siphon loop for the syrup compartment. Ordinarily the valve 39 will be lowered so that there will be no flow of brine through conduit 50 into the secondary tank 16, but at intervals this valve will be raised in response to the action of thermostat 53 so as to supply a quantity of additional cold brine to this tank. In a similar manner, and as already described, the other valve 38 will be periodically opened and closed to admit colder brine to auxiliary tank 21, in response to the net or cumulative temperature changes in the brine in this tank and also in the liquid within the coolers 23 and 24. After the thermostatic elements have been properly set or adjusted, the action is entirely automatic throughout the fountain.

As has been previously noted, the auxiliary tank 21 will be comparatively small so as to permit a rapid change in the temperature of the brine therein, and this has the additional benefit of enlarging the space available for the storage compartment 22. It should be noted that although in the drawings a large portion of this compartment 22 is apparently occupied by the valves and other mechanism that are diagrammatically illustrated, in the actual installation these parts occupy a relatively small space and nearly all of compartment 22 is available for the storage of goods that are to be refrigerated.

In the simplified form of the invention shown in Fig. 7, the brine pump is omitted, and the auxiliary tank 21 is connected with main brine tank 10 by a thermo-siphon loop consisting of the supply pipe 100 and return pipe 101. Cut-off valve 102 controlled by solenoid 103 is positioned in one of these pipes or conduits so as to control the flow of

brine therethrough, and this valve is controlled by the thermostatically operated switch mechanism which may be the same as that disclosed in Figs. 1, 2 and 3.

The modification shown in Fig. 8 is substantially the same as that shown in Fig. 7, except that a motor-driven pump 104 is substituted for the valve 102. When a motor-actuating circuit is completed by the thermostatically operated switch mechanism, brine will be drawn from tank 10 into auxiliary tank 21 through pipe 105, and the warmer brine will be returned to tank 10 through pipe 106. It will be noted that pipes 105 and 106 enter tank 10 at substantially the same level to avoid thermo-siphon action. The discharge pipe 106 may be continued upwardly at 107 within tank 10 to secure the desired circulation of brine within this tank.

In the modification shown in Fig. 9, the auxiliary brine tank 108 which contains the coolers is not connected with the main brine tank 10 for circulation of brine therefrom, but is provided with its own boiler or refrigerating element 109. The supply pipe 110 for the refrigerating medium is not only connected to the main boilers 111 in tank 10, but has a branch line 112 leading to the auxiliary boiler 109 in tank 108. A valve 113 in this supply pipe 112 is thermostatically controlled in response to temperature changes in the coolers and auxiliary brine tank 108, in exactly the same manner as in the previously described modifications. In this form of the invention the temperature of the brine in auxiliary tank 108 is regulated by controlling the refrigerating unit 109 placed therein, this temperature control being quite independent of the temperature of the brine in main tank 10.

In the modification shown in Fig. 10, the auxiliary tank 114 is provided with its own boiler or refrigerating element 115 supplied with refrigerating medium through pipe 112 controlled by valve 113, all as in Fig. 9. In this apparatus the control circuit for operating the valve 113 is controlled by two entirely separate thermostatically controlled switches, one of which 116 is controlled from a bulb 117 placed in one or both of the coolers, and the other 118 is controlled from a bulb 119 in the brine tank. The two switches 116 and 118 are set to close at different temperatures, for example the switch 116 will close when the temperature of the liquid in the coolers to which bulb 117 is exposed has risen to 40° Fahrenheit, whereas switch 118 will close when the temperature of the brine reaches 33° Fahrenheit. In this way, the boiler 115 will be caused to function when either the brine or the liquid in the coolers has risen above certain determined temperatures, the brine always being maintained considerably colder than the liquid that is being cooled. The brine is never permitted to rise above a tem-

perature at which it is cold enough to adequately cool the liquid in the coolers, and if, due to rapid withdrawal of the cooled liquid from the coolers, it is necessary that a lower 5 temperature be established therearound, the switch 116 will close to cause the boiler to function and lower the brine considerably below its normal working temperature until the temperature of the cooled liquid has again 10 been lowered below the permitted maximum. In order to have the modification function rapidly and efficiently, it is desirable that the volume of brine used be comparatively small.

15 For this reason the coolers are here shown of rectangular cross-section to increase their volume relative to tank 114 and are enclosed within the coils of boiler 115. The volume of liquid in the coolers may be approximately 20 the same as the volume of brine in tank 114. It might even be possible to operate this form of apparatus without using brine, the bulb 119 registering the temperature of the boiler coils.

25 As has already been pointed out, other refrigerating elements than the so-called "boilers" here illustrated might be employed for maintaining the original cold temperature of the brine in the main tank, or in the auxiliary 30 tank when direct control of the temperature of the brine therein is used. In the claims which follow, the term "boiler" is intended to cover all such equivalent refrigerating elements. Also other cooling mediums 35 than brine could be employed in the circulatory system, and it is to be understood that the term "brine" is here used by way of example and is intended to cover any equivalent form of temperature controlled liquid. 40 The several tanks and other individual features of the fountain are not all shown in their true sizes or relative proportions in the drawings which are largely diagrammatic.

45 I claim:

1. In a refrigerating apparatus of the character described, a cooler for a fluid, a tank containing brine in which this cooler is immersed, and means for varying the 50 temperature of the brine comprising thermostatic mechanism responsive to the temperatures of both the fluid in the cooler and the brine in the tank.

55 2. In a refrigerating apparatus of the character described, a cooler for a fluid, a tank containing brine in which this cooler is immersed, and means for varying the temperature of the brine comprising thermostatic mechanism responsive simultaneously and 60 cumulatively to the temperatures of the fluid in the cooler and the brine in the tank.

65 3. In a refrigerating apparatus of the character described, a cooler for a fluid, a tank containing brine in which this cooler is immersed, a source of cold brine at a sub-

stantially constant temperature, and means for controlling the flow of cold brine from this source into the tank comprising thermostatic mechanism responsive simultaneously and cumulatively to the temperatures of the 70 fluid in the cooler and the brine in the tank.

4. In a refrigerating apparatus of the character described, a main brine tank, a boiler therein, an auxiliary tank, a cooler for liquid positioned in the auxiliary tank, a conduit for conducting brine from the main tank to the auxiliary tank, a valve in this conduit, a return conduit connecting the tanks, and means responsive to temperature changes 75 in both the auxiliary tank and in the cooler 80 for opening and closing the valve.

5. In a refrigerating apparatus of the character described, a main brine tank, a boiler therein, an auxiliary tank, a cooler for liquid positioned in the auxiliary tank, a conduit for conducting brine from the main tank to the auxiliary tank, a valve in this 85 conduit, a return conduit connecting the tanks, a solenoid for opening and closing the valve, a switch in the solenoid circuit, and thermostatic means in both the auxiliary tank and cooler to operate the switch in response to simultaneous and cumulative 90 changes in the auxiliary tank and cooler.

6. In a refrigerating apparatus of the character described, a main brine tank, an auxiliary tank, a cooler for liquid positioned in the auxiliary tank, a conduit for conducting brine from the main tank to the auxiliary tank, a valve in this conduit, a return conduit 95 connecting the tanks, thermostatic means comprising a bulb in the auxiliary tank, a bulb in the cooler, and an expansible and contractile actuating member, the bulbs and member being interconnected and containing 100 an expansible fluid, and means actuated by the member for operating the valve.

7. In a refrigerating apparatus of the character described, a main brine tank, a boiler therein, an auxiliary tank, a cooler for a liquid positioned in the auxiliary tank, a two-way valve, a conduit leading from the main tank to the valve, a return conduit having branches leading from the auxiliary tank and from the valve to the main tank, a supply 115 conduit leading from the valve to the auxiliary tank, a pump in the first mentioned conduit for forcing brine from the main tank through the conduits, and means responsive to temperature changes in the auxiliary tank 120 for operating the valve.

8. In a refrigerating apparatus of the character described, a main brine tank, a boiler therein, an auxiliary tank, a cooler for a liquid positioned in the auxiliary tank, a two-way valve, a conduit leading from the main tank to the valve, a return conduit having branches leading from the auxiliary tank and from the valve to the auxiliary tank, a supply 125 conduit leading from the valve to the auxiliary tank, a pump in the first mentioned conduit for forcing brine from the main tank through the conduits, and means responsive to temperature changes in the auxiliary tank 130 for operating the valve.

auxiliary tank, a pump in the first mentioned conduit for forcing brine from the main tank through the conduits, and means responsive to temperature changes in both the auxiliary tank and the cooler for operating the valve.

9. In a refrigerating apparatus of the character described, a main brine tank, a boiler therein, an auxiliary tank, a cooler for a liquid positioned in the auxiliary tank, a two-way valve, a conduit leading from the main tank to the valve, a return conduit having branches leading from the auxiliary tank and from the valve to the main tank, a supply conduit leading from the valve to the auxiliary tank, a pump in the first mentioned conduit for forcing brine from the main tank through the conduits, thermostatic means comprising a pair of bulbs and an expansible and contractible member which are interconnected and contain an expansible fluid, one bulb being positioned in the auxiliary tank and the other in the cooler, and means actuated by the expansible member for operating the valve.

25 10. In a refrigerating apparatus of the character described, a main brine tank, a boiler therein, an auxiliary tank, a cooler for a liquid positioned in the auxiliary tank, a two-way valve, a conduit leading from the main tank to the valve, a return conduit having branches leading from the auxiliary tank and from the valve to the main tank, a supply conduit leading from the valve to the auxiliary tank, a pump in the first mentioned conduit for forcing brine from the main tank through the conduits, means responsive to temperature changes in both the auxiliary tank and the cooler for operating the valve, and a thermo-siphon coil leading from the auxiliary tank and returning thereto, a portion of this coil being positioned adjacent the return conduit whereby the temperature of the brine in this portion of the coil will be affected by the temperature of the brine in this return conduit.

11. In a refrigerating apparatus of the character described, a main brine tank, a boiler therein, an auxiliary tank, a cooler for a liquid positioned in the auxiliary tank, a two-way valve, a conduit leading from the main tank to the valve, a return conduit having branches leading from the auxiliary tank and from the valve to the main tank, a supply conduit leading from the valve to the auxiliary tank, a pump in the first mentioned conduit for forcing brine from the main tank through the conduits, thermostatic means comprising a pair of bulbs and an expansible and contractible member which are inter-connected and contain an expansible fluid, one bulb being positioned in the auxiliary tank and the other in the cooler, means actuated by the expansible member for operating the valve, and a thermo-siphon coil leading from the auxiliary tank and return-

ing thereto, a portion of this coil being positioned adjacent the return conduit whereby the temperature of the brine in this portion of the coil will be affected by the temperature of the brine in this return conduit.

12. In a refrigerating apparatus of the character described, a main brine tank, a boiler therein, a second brine tank positioned adjacent the main tank and having an open return flow connection therewith, an auxiliary tank, a cooler for liquids in the auxiliary tank, a pair of two-way valves, a supply conduit leading from the main tank and having branches leading to the respective valves, a pump in this conduit for withdrawing brine from the main tank and forcing it to and through the valves, a return conduit having branches leading from each valve and from the auxiliary tank for returning brine to the main tank, a conduit leading from one valve to the second tank, a conduit leading from the other valve to the auxiliary tank, thermostatic means responsive to the temperature in the second tank for controlling the first valve, and thermostatic means responsive to changes in the temperature in both the auxiliary tank and cooler for operating the second valve.

13. In a refrigerating apparatus of the character described, a main brine tank, a boiler therein, a second brine tank positioned adjacent the main tank and having an open return flow connection therewith, an auxiliary tank, a cooler for liquids in the auxiliary tank, a pair of two-way valves, a supply conduit leading from the main tank and having branches leading to the respective valves, a pump in this conduit for withdrawing brine from the main tank and forcing it to and through the valves, a return conduit having branches leading from each valve and from the auxiliary tank for returning brine to the main tank, a conduit leading from one valve to the second tank, a conduit leading from the other valve to the auxiliary tank, thermostatic means responsive to the temperature in the second tank for controlling the first valve, and thermostatic means comprising a bulb in the auxiliary tank, a bulb in the cooler, and means actuated by the joint action of the expansion and contraction of an expansible fluid in these bulbs for operating the second valve.

14. In a refrigerating apparatus of the character described, a main brine tank, a boiler therein, a second brine tank positioned adjacent the main tank and having an open return flow connection therewith, an auxiliary tank, a cooler for liquids in the auxiliary tank, a pair of two-way valves, a supply conduit leading from the main tank and having branches leading to the respective valves, a pump in this conduit for withdrawing brine from the main tank and forcing it to and through the valves, a return conduit having

- branches leading from each valve and from the auxiliary tank for returning brine to the main tank, a thermosiphon coil leading from the auxiliary tank and back thereto and having a portion thereof positioned adjacent the return conduit whereby the temperature of the brine in this portion of the coil will be affected by the temperature of the brine in the return conduit, a conduit leading from 10 one valve to the second tank, a conduit leading from the other valve to the auxiliary tank, thermostatic means responsive to the temperature in the second tank for controlling the first valve, and thermostatic means comprising a bulb in the auxiliary tank, a bulb in the cooler, and means actuated by the joint action of the expansion and contraction of an expansible fluid in these bulbs for operating the second valve.
15. In a refrigerating apparatus of the character described, a brine tank, a boiler therein, an auxiliary brine tank, a boiler therein, a cooler in the auxiliary tank, a conduit for refrigerating medium having 20 branches leading to the respective boilers, a valve in the branch leading to the auxiliary tank, and thermostatic means responsive to changes in the temperatures in both the auxiliary tank and cooler for operating the 25 valve.
16. In a refrigerating apparatus of the character described, a tank, means for circulating a cooling fluid into and out of the tank, a valve in this circulating means, a cooler for 30 liquid positioned in the tank, and thermostatic means responsive to the combined temperature changes in both the cooler and tank for operating the valve.
17. In a refrigerating apparatus of the character described, a tank, means for circulating a cooling fluid into and out of the tank, a valve in this circulating means, a cooler for liquid positioned in the tank, and thermostatic means comprising a bulb in the 35 cooler, a bulb in the tank and means actuated by the combined expansion or contraction of a fluid in the two bulbs for actuating the valve.
18. In a refrigerating apparatus of the character described, a brine tank, a boiler therein, a conduit for supplying actuating fluid to the boiler, a valve in this conduit, a cooler for liquid positioned in said tank, and thermostatic means responsive simultaneously to the changes in temperature of both the brine and the liquid in the cooler for actuating the valve.
19. In a refrigerating apparatus, a main 40 brine tank, a boiler therein, an auxiliary tank, means for intermittently circulating brine from the main tank through the auxiliary tank, and a thermo-siphon cooling loop leading from and back to the auxiliary tank, the 45 return leg of this loop being so positioned as to be subjected to the temperature of the brine in the main tank.
20. In a refrigerating apparatus, a main brine tank, a boiler therein, an auxiliary tank, means for intermittently circulating brine 50 from the main tank through the auxiliary tank, a thermo-siphon cooling loop leading from and back to the auxiliary tank, and means for circulating brine at the temperature of the brine in the main tank in close 55 proximity to the return leg of the thermo-siphon loop.
21. In apparatus for cooling a fluid to a predetermined temperature, a cooling bath, a cooler located in said bath through which 60 the fluid to be cooled flows, and thermostatically controlled means for lowering the temperature of the cooling bath as the temperature of the fluid in the cooler rises above the predetermined temperature, said thermostatic means being responsive to temperature changes in the bath and also temperature changes in the fluid in the cooler.
